ELECTRICAL SYSTEM FOR INTERNAL COMBUSTION ENGINES

Daniel L. Wertz, Elmira, N. Y., assignor to Eclipse Machine Company, Elmira, N. Y., a corporation of New York

Application April 13, 1932, Serial No. 605,045

3 Claims. (Cl. 290—37)

The present invention relates to an electrical system for internal combustion engines and more particularly to theft protective devices for use in conjunction with automatic starting and ignition control systems.

In automatic control systems for automotive engines, special provisions are sometimes necessary to maintain the protection against theft which is usually incorporated in connection with the ignition system. The present invention embodies an automatic control system in which a single manually operated switch is arranged to control the operation of both the starting and ignition systems, and incorporating theft preventing provisions analogous to those provided in connection with conventional ignition systems.

It is an object of the present invention to provide a novel automatic starting and ignition control system embodying provisions for preventing unauthorized operation thereof.

It is another object to provide such a device in which the automatic starting mechanism is located between the ignition coil and the timer and serves to control the ignition circuit.

A further object is to provide such a device in which a lock switch is employed particularly to control the automatic starting mechanism, and the connections from the switch to the automatic starting mechanism and to the ignition timing mechanism are protected from unauthorized manipulation.

Further objects and advantages will be apparent to those skilled in this art from the following description taken in connection with the accompanying drawing in which the figure is a semi-diagrammatic showing of a preferred embodiment of the invention.

Referring to the drawing, an electrical starting system for an internal combustion engine, not shown, is illustrated comprising a battery 1 grounded at 2 and connected by a lead 3 to a magnetic starting switch indicated generally by numeral 4. Switch 4 is connected by a lead 5 to a single turn coil 6 which is connected by a lead 7 to a starting motor SM, said motor being grounded at 8 to complete the starting circuit.

An ignition system for said engine is illustrated comprising an ignition coil 9 connected through ammeter A to the battery lead 3, and through a manual switch 10 and lead 11 to an automatically operated ignition switch comprising a fixed contact 12 and a movable contact 13. The movable contact 13 which is normally out of engagement with the contact 12 as illustrated is connected by a lead 14 to a timing mechanism of

conventional type indicated generally by numeral 15.

A control circuit for the magnetic starting switch 4 is shown comprising a solenoid 16 connected at one end to the lead 11 and at its other end by a lead 17 to a stationary contact 18. A movable contact 19 is mounted on a spring strip 21 in position normally to engage the fixed contact 18, the spring strip 21 being grounded at 22 to complete the control circuit. Energization of solenoid 16 by closure of the control circuit is arranged to operate a magnetic plunger 20 to close said starting switch 4.

Means are provided for cooperating with said contacts 18, 19 to form a relay for opening said contacts when the engine starts and for closing said contacts if the engine stalls. Said relay includes a solenoid having a battery winding 23 connected at one end by a lead 24 to the starting motor lead 7, and grounded at the other end as indicated at 25. Said solenoid is also provided with a generator winding 26 connected at one end by a lead 27 to an engine driven generator G and grounded at its other end at 25. A plunger 28 is arranged to be actuated by the windings 23 and 26 to swing a lever 29 and cause a roller 31 on the end thereof to engage a weight member 32 on the end of the spring strip 21 and bend the same backward to open contacts 18, 19.

Movable contact 13 of the ignition circuit is mounted on a flexible strip 33 of suitable non-magnetic material which is connected to the magnetic plungers 20 and 28 as indicated at 34 and 35 respectively so that actuation of either of said plungers as above described will move contact 13 into engagement with contact 12 and thereby close the ignition circuit. One end of the strip 33 may if preferred be fixedly supported as indicated at 36. A suitable resistance 37 may be introduced in the ignition circuit beyond the connection to the solenoid 16, as for instance in lead 14, in order to insure that solenoid 16 is properly energized even though the ignition timer 15 should stop with its contacts closed.

In order to prevent unauthorized operation of the device, the manual switch 10 is provided with any suitable or preferred form of locking mechanism, and the lead 11 is provided with a theft resisting sheath 38; the automatic controlling device including the magnetic starting switch and control relay is housed in a casing 39, and the lead 14 to the timing mechanism 15 is also enclosed in a theft resisting sheath 41.

In the operation of the device, closure of the manual lock switch 10 causes the completion of

the control circuit from battery 1 through coil 9 and solenoid 16 to the ground at 22 whereby the plunger 20 is actuated to close the starting switch. Closure of the starting switch causes contact 13 to move into engagement with contact 12 and close the ignition circuit through coil 9, switch 10, and contacts 12, 13 to the timing mechanism 15. The actuation of the starting motor SM by the closure of the starting switch 4 causes the motor to be cranked in the usual manner and closure of the ignition circuit causes the motor to become self-operative.

When the engine starts, the winding 23 of the control relay overcomes the holding effect of the single turn coil 6 in the starting circuit and actuates plunger 28 to swing lever 29 and open contacts 18, 19, thus breaking the control circuit and opening the starting switch 4. The generator winding 26 is energized by the generator G to retain the plunger 28 retracted and hold the contacts 18, 19 open as long as the engine is self-operative. The release of the starting switch 4 does not open the ignition contacts 12, 13 since the retraction of plunger 28 serves to maintain said contacts closed as long as the engine is self-operative.

Should the engine stall for any reason, the generator coil 26 becomes deenergized, releasing the plunger 28 whereby contacts 18, 19 are allowed to close and contacts 12, 13 are allowed to open. The reenergization of the solenoid 16 due to the closure of the control circuit causes the starting switch 4 to be reclosed, whereby the ignition contacts 12, 13 are also closed and restarting takes place as above described.

It will be seen that there is here provided a device whereby a single manual lock switch is enabled to control primarily the starting operation, and secondarily the ignition circuit in conjunction with a switch which is automatically closed by the operation of the starting control mechanism. Since the connections from the lock switch 10 to the control casing 39 and from said casing to the timing mechanism 15 are provided with protective sheaths, it is obvious that this arrangement affords the usual protection from unauthorized operation of the device.

Although but one embodiment of the invention has been shown and described in detail, it will be understood that other embodiments are possible and that various changes may be made

in the details and arrangements of the parts without departing from the spirit of the invention as defined in the claims appended hereto.

What is claimed is:

1. In an automatic control for starting and ignition systems for internal combustion engines, a starting circuit including a starting switch, an ignition circuit including an ignition switch and timing mechanism, an electromagnet for controlling said starting switch, a magnetic relay for opening the starting switch by deenergizing said electromagnet when the engine starts, means whereby said electromagnet causes closure of the ignition switch during the starting operation, and means whereby said relay magnet maintains said ignition switch closed as long as the engine is in operation irrespective of the opening of the starting switch by the deenergization of said electromagnet.

2. In an automatic control for starting and ignition systems for internal combustion engines, a starting circuit including a motor and a starting switch, an ignition circuit including an ignition switch and timing mechanism, an electromagnet for controlling said starting switch, a manual lock switch for closing and opening the circuit of said electromagnet, a magnetic relay for opening the starting circuit by deenergizing said electromagnet when the engine starts, means whereby said electromagnet causes closure of the ignition switch when the starting switch is closed, means whereby said relay magnet maintains said ignition switch closed irrespective of the opening of the starting circuit, and theft-resisting sheathing enclosing and connecting the magnetically operated switches, the manual lock switch and the timing mechanism.

3. In combination with an internal combustion engine, an ignition system therefor including in series an ignition coil, a manual lock switch and a timer mechanism, a starting system for the engine including an automatic starter control located between the ignition coil and timer mechanism, means whereby the automatic starter control closes the ignition circuit during the starting operation and holds it closed during self-operation of the engine, and theft resisting sheathing connecting the manual switch to the automatic starter control and the automatic starter control to the timer mechanism.
